UNITED STATES PATENT OFFICE.

MICHELANGELO BONO, OF NEW YORK, N. Y.

SUSPENDERS.

1,080,534.

Specification of Letters Patent.

Patented Dec. 9, 1913.

Application filed January 31, 1913. Serial No. 745,321.

To all whom it may concern:

Be it known that I, MICHELANGELO BONO, a citizen of Italy, residing at New York city, county and State of New York, have invented new and useful Improvements in Suspenders, of which the following is a specification.

This invention relates to suspenders of novel construction and more particularly to novel and efficient means for securing the tabs to the webbing.

In the accompanying drawing: Figure 1, is a front view of suspenders embodying my invention: Fig. 2, a longitudinal section 15 through one of the front tabs, and Fig. 3, a cross section on line 5, 5, Fig. 2.

The device consists essentially of a continuous strip of webbing 10 of a length sufficient to form the two shoulder straps of a pair of suspenders. At one of its ends, the webbing carries a hook 11, while at its other end it carries an eye 12 adapted to be engaged by the hook when the device is to be worn in the form of a belt. In order to 25 secure the hook to the webbing, one end of the latter is drawn through a slotted slide 13 and is then fastened by a bent wire clasp 14. Over the protruding end of slide 13 is slipped a slotted frame 15, while the upper corrugated plate-like section 16 of hook 11 is introduced between the slide and plate, said upper section being provided with laterally extending shoulders 17 adapted to engage the slide. In like manner, the upper 30 plate-like and corrugated section 18 of eye 12 has shoulders 19 and is detachably secured to the other end of the webbing by means of slide 13, frame 15 and clasp 14.

The duplex front tabs 20 slotted as at 34 and adapted to support the trousers, carry an intermediate tab adapted to support the drawers. This intermediate tab comprises a tubular casing 21, the lower flat apertured end 22 of which is adapted to be passed back 45 of a tape on the drawers and to be thence secured to a stud 23 projecting from the tab. Within casing 21 is housed a spiral spring 24 which encompasses a plunger rod 25 having a foot 26 below the spring and 50 extending upwardly through an apertured plate 27 fitted into the upper end of the casing. Rod 25 thence passes through a reinforcing ring 28 encircling tab 20 and through the body of said tab, said rod having an upper bent end or beak 29. By the

construction described, all objectionable springs located above the tabs, *i. e.* between the tabs and the webbing are dispensed with, while nevertheless an efficient yielding relation between the webbing and all of the tabs 60 is provided for. That is to say, under strain, the resulting pull on the webbing will cause an upward movement of plunger 25 within plate 27 and ring 28, thereby compressing spring 24, and thus providing the desired 65 resilient action. That tab which is to depend from hook 11 is further provided with a plate 30 having a slot 31 adapted to be engaged by hook 11 and an aperture 32 adapted to be engaged by beak 29. With 70 that tab which is to depend from eye 12, plate 30 is omitted, the beak 29 of its plunger 25 passing directly through an aperture 33 of eye 12. It will be seen that the tabs may be readily attached to and removed 75 from the hook 11 and eye 12 respectively and that in addition to providing means for sustaining the trousers, the tabs present strong resilient and readily operable means for sustaining the drawers. 80

At its center, there is fitted upon the webbing 10, a removable slide 42 having an elongated slot for the reception of the webbing. This slide is removably engaged by the upper bent ends 43 of a bail 44 from 85 which the rear tabs 45 are suspended. These rear tabs may be provided with a tubular casing 46 inclosing a spring plunger 47 constructed similar to plunger 25 and having an upper bent end 48 which is hooked over 90 bail 44. Slide 42 may be removed by first removing the clasp 14 and slide 13 together with its hook or eye from one end of webbing 10, and then slipping slide 42 off said end. 95

I claim:

Suspenders comprising a webbing, a plunger depending therefrom, a duplex trouser-engaging tab having a centrally apertured shank that accommodates the 100 plunger, a tubular drawers-engaging tab inclosing the plunger below the shank of the first named tab, and a spring interposed between the lower end of the plunger and the upper end of the tubular tab.

MICHELANGELO BONO.
